CAN CARTON

Ben H. Larsen, Minneapolis, Minn.

Filed Feb. 23, 1961, Ser. No. 64,025

Term of patent 14 years

(Cl. D58—26)

FIG. 1 is a perspective view of a can carton, showing my new design;

FIG. 2 is a front elevational view thereof;

FIG. 3 is a side elevational view thereof; and

FIG. 4 is a top plan view thereof.

FIG. 5 is a sectional view taken on line 5—5 of FIG. 2.

A side elevational view of the opposite side of my can carton is substantially identical to FIG. 3 and a bottom plan view is substantially identical to FIG. 4.

I claim:

The ornamental design for a can carton, as shown and described.
